ELECTROLYTIC APPARATUS.

1,186,936.

Specification of Letters Patent. Patented June 13, 1916.

Application filed June 18, 1913. Serial No. 774,039.

To all whom it may concern:

Be it known that we, JOHANNES PFLEGER and FRIEDRICH OTT, both subjects of the Emperor of Germany, and both residents of Frankfort-on-the-Main, Germany, have invented certain new and useful Improvements in Electrolytic Apparatus, of which the following is a specification.

This invention relates to an improvement in electrolytic apparatus for the production of alkali metal, such as metallic sodium, from molten alkali halogenids, such as sodium chlorid, and it refers particularly to the protection of an essential part of the apparatus against the harmful action of the halogen, such as chlorin gas, generated in the process.

The well known apparatus of Castner for the production of alkali metal by electrolyzing fused alkali at a temperature only slightly above the melting point of the alkali, as described in United States Patent No. 452,030, German Patent No. 58,121, etc., operates satisfactorily, but the high price 25 of the raw material used is a handicap for the production of the metal at a lower price than at present, and if one selects cheaper substitutes for Castner's raw material precautions must be taken that such substitute shall form no products at the anode during the electrolysis which might attack the apparatus, such as chlorin gas for example.

The essential characteristics of the Castner process include the following: (1) the use of a wire net as a diaphragm; (2) the step of bringing the alkali metal separated by the electrolytic process, out of contact with the cathode. Attempts have been made to apply these essential characteristics of the 35 Castner apparatus also to the electrolysis of alkali halogenids, such as sodium chlorid. This problem was solved, according to German Patent No. 236,804, by using two partitions separated from each other, made 40 from different materials, differently formed and located at certain places in the apparatus for the separation of the products by the electrolysis. Such an arrangement represents, however, only a complication of the 45 Castner apparatus and of the method of operating the same.

We have now found that the complication, pointed out above, is not at all necessary in making said apparatus suitable for

the electrolysis of alkali halogenids. This 55 recognition is based on the surprising observation that there is no other hindrance to the application of the Castner apparatus to the electrolysis of said alkali-halogenids but the fact that the outside of the vessel 60 of the apparatus, which serves as a collector for the alkali metal generated by the electrolysis and furthermore brings the alkali metal out of contact with the cathode, is exposed to the destroying action of the halogen, such as chlorin, generated at the anode, and that one may easily and economically electrolyze alkali halogenids without the inconvenient means and steps shown by German Patent No. 236,804, if one covers 70 the collector with a coat of halogen-proof or, in the case of the electrolysis of an alkali chlorid, of chlorin-proof material, down to or somewhat below the level of the electrolyte.

For the better understanding of our invention, reference is made to the accompanying drawing, which represents a sectional elevation of a convenient form of apparatus for carrying our invention into effect.

The apparatus comprises a receptacle A, of iron or any other suitable material, which serves as a container for the electrolyte as well as for the electrodes with the other appurtenances necessary thereto. The cathode 85 1, of iron or any other suitable material, is entered preferably from below through the bottom of A and extends upward into the vessel from which it is suitably insulated. The anode 2, preferably made of carbon, is 90 suspended at the top of the vessel, insulated from same by suitable material, and passes downward until the working surface at its lower end is opposite to that of cathode 1. The electrodes 1 and 2 are separated by a 95 wire screen 3 which is connected with an iron receptacle 4, the upper end of which is closed by a lid.

The electrolyte reaches somewhat below the rim of vessel A and leaves ample space 100 between anode and receptacle 4 into which the chlorin gas escapes. The outside of the receptacle 4 which is exposed to said chlorin gas is covered with a layer 5, made of material resistant to chlorin, said layer reaching somewhat below the level of the electrolyte. Inside receptacle 4 the level of the electrolyte is somewhat higher than outside,

owing to the low specific gravity of the metal 3 as obtained by the process. The chlorin gas generated escapes through pipe 7. The metal obtained by the electrolysis may be 5 removed in any of the well known ways, either by dipping same out or by providing a contrivance for the drainage of said metal.

Such a Castner apparatus, if provided 10 with a protective coat on the outside of the collector as pointed out above, becomes a universal apparatus for the electrolytical production of alkali metals, as this modified Castner apparatus does not require one to 15 pay attention to harmful anode-products and thus permits the use of cheap raw materials.

The protection of the vessel, acting as a 20 collector for the sodium, in the electrolysis of sodium chlorid, against the action of the chlorin is illustrated by the following example showing one of the ways by which we carry our invention into effect.

Asbestos-thread is impregnated with a 25 thin paste-like mixture of water glass and asbestos-flour, and is then wound around the vessel, and is ready for use when dried.

We do not restrict ourselves to the use of 30 any particular halogen-proof material or to the practice of the process carried out in connection therewith with any particular alkali

halogen, further than the scope of the appended claims demands.

What we claim and desire to secure by Letters Patent is:

1. In an apparatus for the electrolysis of fused alkali salts, the combination with positive and negative electrodes having their working faces in close juxtaposition to each other, of a gauze or screen interposed between said electrodes, a superposed vessel 40 or dome for receiving the separated metal and a halogen-resisting coating on the outer surface of said receiving vessel.

2. In an apparatus for the electrolysis of fused alkali salts, the combination with positive and negative electrodes having their working faces in close juxtaposition to each other, of a gauze or screen interposed between said electrodes, a superposed vessel or dome for receiving the separated metal and 50 a chlorin-resisting coating on the outer surface of said receiving vessel.

In testimony whereof we have signed this specification in the presence of two subscribing witnesses.

JOHANNES PFLEGER.
FRIEDRICH OTT.
